UNITED STATES PATENT OFFICE.

THOMAS S. HOMANS, OF HEMPSTEAD, NEW YORK, ASSIGNOR TO INTERTYPE CORPORATION, OF BROOKLYN, NEW YORK, A CORPORATION OF NEW YORK.

TYPOGRAPHICAL MACHINE.

1,338,628.

Specification of Letters Patent. Patented Apr. 27, 1920.

Application filed February 19, 1919. Serial No. 278,037.

To all whom it may concern:

Be it known that I, THOMAS S. HOMANS, a citizen of the United States, residing at Hempstead, Long Island, in the county of 5 Nassau and State of New York, have invented new and useful Improvements in Typographical Machines, of which the following is a specification.

My present invention relates to improvements in typographical machines and more especially to those of the linotype class, it pertaining more particularly to the means for mounting the magazines in which the matrices are stored and from which the 15 matrices are drawn for use and to which they are returned after use.

While the invention is applicable to magazines of various styles and forms it is herein shown applied to an auxiliary or side magazine attachment such as that disclosed in my co-pending application Serial No. 155,267, filed March 16, 1917, the present improvements presenting the practical advantage of increasing the magazine capacity and hence 25 the range of usefulness of such an attachment by providing means for supporting a plurality of magazines in such position that any one of such magazines may be quickly brought into position for use with a minimum amount of labor on the part of the 30 operator or attendant.

To these and other ends, the invention consists in certain improvements and the combinations and arrangements of parts, all 35 as will be more fully hereinafter described, the features of novelty being pointed out particularly in the claims at the end of the specification.

In the drawings:—
40 Figure 1 is a side elevation of a side magazine attachment or unit showing a magazine mounting embodying the present invention.

Fig. 2 is a front elevation of the side magazine attachment or unit embodying the improved magazine mounting.

Fig. 3 is a perspective view of one of the magazines.

Fig. 4 is a perspective view of the magazine holder with the magazines removed therefrom, and

Fig. 5 is a perspective view of the yoke

and spindle on which the magazine holder is mounted.

Similar parts are designated by the same reference characters in the several views.

Magazine arrangements embodying the present invention are applicable generally to typographical machines of the linotype class, although the invention is particularly adapted for use in connection with a side magazine unit or attachment such as that shown and described in my co-pending application referred to. In that application the side magazine unit accommodates one magazine, whereas the present invention enables the side magazine unit to accommodate a plurality of magazines, any one of which may be easily and quickly brought into operative relation with the assembling and distributing mechanisms without the necessity of removing the magazines from the machine. The preferred embodiment of the invention is shown in the accompanying drawings and will be hereinafter described in detail but it is to be understood that the invention is not restricted to the precise construction shown, as equivalent constructions are contemplated and will be included within the scope of the claims.

In the present instance 1 designates a portion of the main frame of the machine to which the side magazine unit is applied and 2 designates the frame of the side magazine unit, the frame being pivoted to the main frame of the machine at the points 3 and 4, a fastening or lock 5 serving to retain the side magazine unit in operative relation with the machine to which it is applied. 6 represents the distributing mechanism of the side magazine unit, this distributing mechanism being a continuation of or auxiliary to the distributing mechanism to the main machine, and 7 designates the matrix-assembling mechanism which is auxiliary to the matrix-assembling mechanism of the main machine. The construction and mode of operation of the side magazine unit and its co-operative relation with the machine to which it is applied are fully shown and described in my co-pending application referred to. In that application, however, a one-piece magazine is shown extending from the distributing mechanism to the assem-

bling mechanism. In the illustrated embodiment of the present invention, relatively short magazines are used and a magazine section m is fitted to the machine to fill the space between the distributing mechanism and the upper end of the magazine whereby the matrices will be conducted from the distributing mechanism into the magazine which happens to be in operative position.

10 The present invention provides means whereby a plurality of magazines can be accommodated at one time in the machine and any one of these magazines may be readily brought into an operative position between the upper magazine section m and the assembling mechanism 7. While different numbers of magazines may be accommodated it is preferable to provide for three magazines as shown in the present instance.

15 The magazine mounting comprises a frame 8 which is preferably three-sided, providing three sides upon which the magazines may be placed. The corners of the magazine frame are preferably flattened as shown and these flattened corners of the frame are provided with pairs of upper and lower upwardly turned hooks 9 which are arranged to receive the laterally projecting ends of

20 rails 10 which rails are fixed to the undersides of the magazines. With this arrangement any one or more of the magazines may be removed from the magazine frame by sliding the magazine upwardly until the cross-rails 10 thereof are disengaged from the retaining hooks 9 whereupon the unfastened magazine can be elevated from the machine. The placing of a magazine on the magazine frame is accomplished by a reverse operation.

25 The magazine frame is revolvably mounted on a spindle 11 which fits and extends through an upper bearing 12 formed in the magazine frame, the spindle being provided with a threaded portion to receive nuts 13 which are adapted to abut against the forward or lower end of the bearing 12 of the magazine frame and thereby position the magazine frame in a forward and rearward direction. The spindle 11 is attached

30 to a yoke 14 and this yoke is pivoted by a pin 15 to the forward end of an arm 16. This arm 16 is pivoted at 17 to the lugs 18 which are attached to the frame 2 of the side magazine unit and the upper end of

35 the frame 16 cooperates with an adjusting screw 19, the screw being fixed to the side magazine unit frame 2 and provided with an adjusting nut 20 which cooperates with the upper end of the arm 16, thus providing

40 means for adjusting the elevation of the pivot pin 15 to which the yoke 14 is connected. The yoke 14 straddles the lower end of the arm 16 and a cross-bar 21 connects the arms of the yoke as adapted to abut

45 against the upper side of the arm 16 when

the yoke is swung upwardly about the pivot 15 as an axis, this cross-bar thereby limiting the upward swing of the magazine. To facilitate manipulation of the magazine frame, the latter is provided in the present instance with a handle 22 which extends forwardly and in line with the axis of rotation of the magazine frame, the handle providing convenient means for lifting the magazine frame and the magazine units thereof into the upper position indicated by the dotted lines in Fig. 1 and for rotating the frame and magazines while in raised position to bring the desired magazine into position for use. Preferably and as shown the shank or stem 23 of the handle 22 is fitted into a bearing or boss 24 on the magazine frame which is in alignment with the bearing 12, this shank 23 being fixed in the bearing 24 with its rear end spaced forwardly from the forward end of the spindle 11 so as to allow clearance for adjusting the magazine frame axially on the spindle. The forward end of the spindle may, as shown, enter the rear end of the forward bearing 24 in order to provide a steady bearing for the magazine frame. Lateral positioning of the magazine in use is effected by lugs 25 which are fixed to the frame 2 of the side magazine unit and are arranged to cooperate with the opposite edges of the magazine when the latter is brought into operative position.

50 The operation of changing magazines is as follows:—

55 The magazine frame which contains the relatively short matrix containing magazine section is first lifted upwardly by the handle 22, the frame and the magazines thereof swinging into the position shown by the dotted lines in Fig. 1 about the pivot pin 15 as the axis, this upward movement of the magazine frame and the magazines thereof being limited by the engagement of the cross rod 21 on the yoke 14 with the upper side of the arm 16. While the magazine frame is held in elevated position, it is rotated about the spindle 11 as the axis until the desired magazine thereon assumes a position directly beneath the spindle 11. The magazine frame is then lowered causing the selected magazine to assume a position between the lower end of the upper magazine section m and the assembling mechanism 7, it being understood that the matrix containing magazine sections of the magazine are provided with escapements controlling the delivery of the matrix therefrom and that these escapements are brought into operative relation with the key-board mechanism as the respective magazine section is brought into operative position. The adjustment 19—20 enables the spindle 11 to be so set as to insure correct registration of the magazines thereof with the upper magazine sec-

tion m and the matrix delivery mechanism 7.

By mounting the relatively short matrix-containing sections of the magazine on the 5 magazine frame, and locating the pivot 15 of the magazine frame forward of the rear or upper ends of the magazines, as shown, the lifting effort required to elevate the 10 magazines and their frame to effect a change of magazines is reduced to a minimum, the location of the pivot 15 being such that the weight of the magazines is partly counterbalanced. Furthermore, the symmetrical 15 arrangement of the magazines above the spindle balances the magazines and a minimum effort is required to rotate them and 20 their carrying frame. The means provided for effecting axial adjustment of the magazine frame on its spindle, enables the magazines to be accurately positioned in a direction longitudinally of the magazine section m , while, as previously explained, the 25 adjustment 19—20 enables the rear edge of the magazine in operative position to be elevated or lowered as may be necessary, to bring such edge into alignment or register with the lower forward edge of the magazine section m . The forward portion of the 30 magazine on the magazine frame comes to rest on a stop 26 as such magazine assumes its operative position, thus setting its escapements in correct operative relation with the keyboard mechanism.

I claim as my invention—

35 1. In a typographical machine, a frame having means for supporting a plurality of matrix-containing magazines thereon, and a shaft about which said frame is rotatable to bring any one of the magazines thereon into a predetermined position, the shaft being pivoted to swing in a direction transversely of its axis to carry a selected magazine into or out of operative position.

40 2. In a typographical machine, a frame having a plurality of sides to receive and support a number of magazines, a shaft located in symmetrical relation to said magazines and about which said frame is rotatable to alter the position of the magazines 45 relatively to the distributing and assembling mechanisms of the machine, said shaft being shiftable in a direction transversely of its axis to move any one of the magazines on said frame into or out of operative 50 position relatively to the distributing and assembling mechanisms.

55 3. In a typographical machine, a frame adapted to carry a plurality of magazines, a spindle on which said frame is adjustable 60 to bring any one of the magazines thereon into position for use, and an adjustable member connected to said spindle for positioning the frame and a magazine thereon

in correct operative relation with the assembling and distributing mechanisms of 65 the machine.

4. In a typographical machine, a frame adapted to carry a plurality of magazines, a shaft on which said frame is rotatable to bring any one of the magazines thereon into 70 operative position, means for adjusting said shaft in a direction transversely of its axis, and means on said shaft for adjusting the axial position of the frame thereon.

5. In a typographical machine, a frame 75 adapted to carry a plurality of magazines, a shaft located centrally of said magazines and on which said frame is rotatable to bring any magazine thereon in position for use, and a member pivotally supporting one 80 end of said shaft and adjustable to secure registration of a magazine on said frame with the assembling and distributing mechanisms of the machine.

6. In a typographical machine, a frame 85 adapted to carry a plurality of magazines, a shaft on which said frame is rotatable, means for adjusting the position of said frame axially on said shaft, and means pivotally supporting said shaft and adjustable 90 to vary the position of the shaft in a direction transversely of its axis.

7. In a typographical machine, a frame 95 adapted to support a plurality of magazines in symmetrical relation thereon, and a shaft 100 rotatably supporting said frame and located centrally and longitudinally of the magazines, said shaft being pivoted at one end whereby it may swing any desired magazine on said frame into and out of operative position.

8. In a typographical machine comprising a main frame and distributing and assembling mechanisms mounted thereon, a magazine frame having a plurality of sides 105 each adapted to receive a matrix magazine, and a support on which said magazine frame is rotatable to bring any one of the magazines thereon into position for use, said support being movable relatively to the main 110 frame in a direction transversely of the axis of rotation of the magazine frame, whereby the magazine selected for use may be moved into and out of co-operative relation with the distributing and assembling mechanism, 115 the main frame providing a support for the selected magazine when the same is in position for use.

In testimony whereof I have hereunto set my hand in presence of two subscribing 120 witnesses.

THOMAS S. HOMANS.
